BIRD CAGE

Sidney Herman, Los Angeles, Calif., assignor to Continental Cage Corporation, Culver City, Calif., a corporation of California

Application November 1, 1954, Serial No. 32,896

Term of patent 14 years

(Cl. D31—2)

Fig. 1.

Fig. 2.

Fig. 1 is a front perspective view of a bird cage illustrating my new design, and showing the top and one side thereof, and Fig. 2 is a back perspective view of the cage shown in Fig. 1, showing the bottom and the other side thereof.

I claim:

The ornamental design for a bird cage, as shown.
